UNITED STATES PATENT OFFICE.

CHARLES B. BRANSON, OF LINCOLN, NEBRASKA.

CONSTRUCTIVE DESIGN OF FACE-PLATES USED FOR THE PURPOSE OF COVERING OPENINGS IN AIR-REGISTERS AND VENTILATORS THROUGH WHICH AIR PASSES.

1,313,460.

Specification of Letters Patent.

Patented Aug. 19, 1919.

Application filed May 12, 1919. Serial No. 296,353.

To all whom it may concern:

Be it known that I, CHARLES B. BRANSON, a citizen of the United States, residing at Lincoln, in the county of Lancaster and State 5 of Nebraska, have invented a new and useful improvement in the constructive designs of face-plates used for the purpose of covering openings in air-registers and ventilators through which air passes.

10 The object of my invention is to provide a device or face plate to cover the opening in air registers and ventilation shafts which will permit a maximum quantity of air to pass through, with the minimum of resistance, friction and heat absorption. It is further my object to increase the strength of the device while minimizing the surface area occupied by its elements. I attain the 15 object of my invention by the mechanical construction illustrated in the accompanying drawings, in which—

Figure 1 is a vertical section of the invention;

Fig. 2 is a rear face view of same;

25 Fig. 3 is a vertical section of a modified form of the invention;

Fig. 4 is a rear face view of the form shown in Fig. 3; and

30 Fig. 5 is a rear face view of the invention applied to a curved or ornamental plate.

Like numerals designate like parts in the several views.

Referring to the accompanying drawings, I provide a suitable frame 1 having any 35 desired arrangement or configuration of bars. Each of these bars comprises a face 4 and rearwardly tapering sides 2 and 3, as illustrated in Figs. 1 and 2. The bars may be curved, as shown in Fig. 5, but retain 40 the same shape in cross section.

In case of the application of the invention to an intake, it is understood that these bars will be disposed in a reverse position.

Referring to Figs. 3 and 4, I may provide 45 a modified form of bars having one of the sides 6 disposed at right angle to the face 4 of the bar and having the opposed side 5 tapering to meet the face 6. This construction would be largely employed in side wall

face plates, to offer the least resistance to 50 the passage of a current of heated air, in particular, in view of the tendency of hot air to rise.

In operation a sharp edge 7 is presented to the air current, diverting it to the tapering sides 2 and 3 (or 5 and 6) with little deflection, resistance or friction. With this improved construction the bars may be spaced farther from each other as the necessary strength is obtained by the increased 55 depth of the bar instead of by a wider face surface as in prior constructions. An important advantage is thus obtained by decreasing the obstruction to the flow of the air current. 60

Practically all face plates in use present a very much flattened rear surface which opposes the entrance of air, thus creating resistance and friction and an undesirable loss of heat, which result is largely overcome 70 by the peculiar shape of the bars disclosed in my application. In each of the forms disclosed a sharp edge 7 is presented to the air current, diverting it to the side with little deflection, resistance or friction. 75

The invention is applicable to all face plate constructions for air registers and ventilators and involves little or no extra expense for manufacture.

I am aware that plates have heretofore 80 been devised with bars of various irregular shapes in cross section, but these devices do not attain the advantages of the construction I have illustrated; nor do the patents covering these devices suggest the possibility 85 of making a modification of the shape or constructive design of the face plates for the purpose of minimizing their obstruction to the air passing through the registers or ventilators; nor has the result attained by applicant's device been understood or recorded by prior inventors, so far as he is aware. 90

What I claim is:

1. In a device of the class described, the combination of a frame, intersecting bars of 95 any desired surface configuration, each of said bars being triangular in cross section and having continuous rearwardly tapering

sides terminating in sharp edges presented to the air current to present the minimum of obstruction to the air current while providing bars of increased strength.

- 5 2. A face plate for ventilators and registers having a plurality of bars of complete wedge shape in cross section and having the

apex of the wedge directed toward the air current, whereby to minimize friction and resistance and to increase the strength of the 10 bars by increased depth, permitting of their being spaced farther apart.

CHARLES B. BRANSON.
